UNITED STATES PATENT OFFICE.

HYMAN D. WEISSBERG, OF NEW YORK, N. Y.

DESIGN FOR A BIRD CAGE.

Application filed February 16, 1928. Serial No. 25,454. Term of patent 3½ years.

To all whom it may concern:

Be it known that I, HYMAN D. WEISSBERG, a citizen of the United States, residing at New York, in the county of New York and State of New York, have invented a new, original, and ornamental Design for a Bird Cage, of which the following is a specification, reference being had to the accompanying drawing, forming a part thereof.

Fig. 1 is a front view of a bird cage, showing my new design.

Fig. 2 is a top plan.

I claim:

The ornamental design for a bird cage, as shown.

HYMAN D. WEISSBERG.
